United States Patent Office

Des. 195,722

Patented July 23, 1963

195,722

ELECTRICAL CONNECTOR

Edgar W. Forney, Jr., 2405 Paxton Church Road,
R.D. 2, Harrisburg, Pa., and Richard S. Hogendobler,
6 Nottingham Drive, Camp Hill, Pa.

Filed Nov. 28, 1961, Ser. No. 67,725

Term of patent 14 years

(Cl. D26—1)

FIGURE 1 is a perspective view of an electrical connector embodying our new design;

FIGURE 2 is a top view of the device shown in FIGURE 1;

FIGURE 3 is a side view of the device shown in FIGURE 1; and

FIGURES 4 and 5 are end views of the device shown in FIGURE 1.

We claim:
The ornamental design for an electrical connector, substantially as shown.
